UNITED STATES PATENT OFFICE.

WILLIAM E. TAYLOR, OF EASTPORT, MAINE, ASSIGNOR TO AMERICAN CAN COMPANY
OF NEW YORK, N. Y., A CORPORATION OF NEW JERSEY.

AUTOMATIC-FEED CAN-BODY MACHINE.

942,190.

Specification of Letters Patent.

Patented Dec. 7, 1909.

Application filed March 24, 1909. Serial No. 485,362.

To all whom it may concern:

Be it known that I, WILLIAM E. TAYLOR, a citizen of the United States, residing in Eastport, in the county of Washington and State of Maine, have invented a new and useful Improvement in Automatic-Feed Can-Body Machines, of which the following is a specification.

My invention relates to improvements in can body making machines.

The object of my invention is to provide a machine of a simple, efficient and durable construction, which will operate to automatically feed the blanks one by one from a stack or pile in a suitable magazine or holder and form them into can bodies having lock side seams at the middle portion and lap side seams at the end portions of the bodies and to solder such side seams; the machine of my invention being especially designed and intended for production of sardine can bodies, the blanks for which are long and extremely narrow and flimsy, the same being ordinarily a foot or more in length while only about an inch in width.

My invention consists in the novel construction of parts and devices and in the novel combinations of parts and devices herein shown and described and by which it is adapted to operate accurately and successfully upon the long, narrow, flimsy can body blanks employed in making sardine can bodies.

In the accompanying drawing forming a part of this specification, Figure 1 is a plan view of a sardine can body machine embodying my invention, a portion of the soldering mechanism being broken away. Fig. 2 is a front elevation. Fig. 3 is a central vertical longitudinal section on line 3—3 of Fig. 1. Figs. 4, 5, and 6 are detail vertical sections on lines 4—4, 5—5 and 6—6 respectively of Fig. 3. Fig. 7 is an enlarged detail longitudinal section of the body blank feed mechanism showing the blank carrier at its extreme backward stroke. Fig. 8 is a similar view showing the body blank carrier at its extreme forward stroke. Fig. 9 is an enlarged detail elevation showing the body blank feed mechanism. Fig. 10 is a detail plan view of the can body blank after it has been notched by the notching dies. Fig. 11 is a perspective view of the blank after the edge folds have been formed thereon and Fig. 12 a perspective view of the

lock and lap seam can body produced by the machine. Fig. 13 is a detail vertical cross section on line 13—13 of Fig. 3.

In the drawing, A represents the frame of the machine, B the body blank separator, C the magazine or holder for the blanks, D the push-off finger or body blank feeder, E the reciprocating carrier for the body blanks, furnished with a plurality of fingers or pawls E¹, F the tension shoes, F¹ the guides, G G¹ the notching dies, H H¹ the edge folders or hook forming devices, I the body former horn, K the wings or formers for forming or wrapping the blank around the body former horn, L the bumper or seam squeezer, M the soldering horn, N the fluxing device, O the soldering pot, P the solder feed device, R R¹ conveyors for moving the can bodies along the soldering horn and S the main driving shaft of the machine.

The frame A of the machine may be of any suitable kind or construction adapted to give support to the other parts of the machine.

The separator B is arranged under the lower end of the blank holder or magazine C and is secured to the frame by suitable plates or screws b. It has an inclined upper face b¹ upon which the lowermost blank x of the stack or pile X rests in an inclined and separated and slightly advanced position from the other blanks in the stack or pile of blanks X, adapting it to be engaged with certainty and regularity by the fingers or pawls E¹ of the carrier E. The separator B also has a narrow ledge or shoulder b² upon which the rear edge of the stack or pile of blanks X rests, the front edge of the stack or pile resting upon the inclined separator face b¹ of the separator B. The separator B is provided with a top or upper portion B¹ which may preferably also form the rear guide or wall of the blank holder or magazine C. And a slot or opening b³ is left between the lower end or edge b⁴ of this top or upper portion B¹ of the separator and the inclined face b¹ of the separator sufficient to permit the lowermost blank of the pile to be fed or pushed slightly forward by the push-off finger or feeder D sufficiently to disengage it from the ledge or shoulder b² upon which the rear edge of the pile of blanks rests, and thus permit the lowermost blank to rest on the inclined face b¹ of the separator in position to be properly engaged.

by the fingers or pawls E¹ of the carrier E. The top or upper portion B¹ of the separator B is adjustably secured in proper relation to the inclined face b¹ of the separator B by means of a supporting bar B², bolt B³ and adjusting screws B⁴. The separator B is also provided with a tension shoe or finger b⁵ having a spring b⁶ which presses down upon the blank as it is carried forward by the carrier E.

The blank magazine or holder C may be of any suitable kind or construction, and its front guides or walls C¹ may extend at their lower ends down to the upper face of the separator B.

The push-off finger or feeder D is preferably reciprocated as required to push the lowermost blank of the pile off the narrow ledge or shoulder b² of the separator B by connecting it directly to the carrier E by screw bolts d. A plurality of the feeders or fingers D are preferably employed, each secured to one of the bars of the carrier E, and each having a curved or runway shaped front end to adapt it to ride or pass readily under the stack or pile of blanks X in the holder C, and each also provided with a blank engaging device or shoulder d¹, preferably of hardened steel, and secured to the feeder D by a screw d². The blank engaging device or shoulder d¹ projects above the upper face of the feeder or push-off finger D just the thickness of one blank x so that only the lowermost blank of the stack or pile can be engaged by the push-off finger or feeder D.

The blank carrier E may be of any suitable construction, but it preferably consists of a plurality of reciprocating bars, each furnished with a plurality of pivoted pawls or fingers E¹, each having a light spring E² for holding it in its normal position while permitting it to readily ride under the blanks. The several pawls E¹ on each feeder bar advance or carry the blanks forward step by step from one station to another to enable each blank to receive successively the required notching, edging and body forming operations. The carrier E is preferably reciprocated as required by means of a cam or eccentric S¹ on the main cam shaft S through suitable connecting devices as link E³, lever E⁴ and links E⁵ E⁶.

The tension shoes or devices F are arranged above the bars of the carrier E and operate to hold the body blanks straight and flat against the upper face of the carrier bars, and thus insure the blanks being properly presented to and in accurate registry with the notching dies, edging devices or hook formers, and the body former horn and wings or body formers. The shoes or tension bars F preferably have inclined front ends f to insure the proper entry of the body blanks under the same. And the

same are furnished with springs f¹ to press them yieldingly down against the body blanks, and they are preferably so supported from stationary arms F² through connecting bolts F³. The guides F¹ for the body blanks also aid in insuring the blanks being presented by the carrier E in proper registry with the notching dies, edge folders, body former horn and body formers.

The notching dies G G¹ serve to notch and clip off the corners of the body blanks so that the hooks or edge folds will not be formed upon the extreme end portions thereof, but only upon the middle portion, and thus cause the can body to be produced from such blank to have a lock side seam at the middle portion of the seam and a lap side seam at the two end portions of such seam. These notching dies preferably comprise stationary members G secured to the frame of the machine, and movable or reciprocating dies G¹ carried by a vertically movable slide or cross head G² which is preferably operated from a cam G³ on the shaft S through suitable connecting mechanism as lever G⁴ and link G⁵. The cross head G² reciprocates in suitable guides G⁶ on the frame of the machine.

The edge folders or hook forming devices H H¹ may be of any suitable kind or construction customarily employed in can body making machines, but preferably consist of two pairs of dies, one pair for each extremity of the body blank x, the upper die H of each pair being secured to the stationary frame of the machine, and the two lower dies H H¹ being carried by a movable cross head or slide H² which is preferably operated by a crank arm S² on shaft S through the connecting pitman H³. The hook forming or edge folding dies H H¹ for each end of the blank are alike, but oppositely turned, so that one pair of these dies forms an upturned hook or edge fold x¹ on one end of the blank, while the other pair of dies forms a downturned hook or edge fold x² on the opposite end of the blank; so that when the blank x is wrapped around the body former horn I by the wings or formers K, the hooks x¹ x² will interengage and thus cause the bumper or seam squeezer L to form the customary lock seam at the middle portion of the blank. At the ends or corners of the blank where the notching dies G G¹ produce the notches x³ x⁴ in the blank, the side seam of the formed can body is of the ordinary lap seam type. This adapts the body to be suitably flanged and to have the top and bottom heads of the sardine can secured to the body by an interfolded or double seam.

The body former horn I may be of any suitable or well known construction customarily employed in can body making machines. It is movably mounted on the frame

of the machine by a suitable arm I^1 and is moved up and down slightly by a cam I^2 to clamp the blank against the stationary block I^3 . It is of rectangular shape with rounded corners to produce the can body of the customary sardine can shape.

The wings or body formers K which operate to wrap or fold or form the can body blank downward around the horn I are shaped to conform thereto, and are each preferably hinged at K^1 to the frame of the machine above the upper corners of the horn, and are operated as required by means of an eccentric S^3 on the main shaft S through the connecting strap K^2 and connecting rods K^3 , K^4 , the connecting rod K^4 having a spring K^5 interposed to give a yielding connection between said rod K^4 and the strap K^2 and thus enable the wing K which is operated by said rod K^4 to close slightly in advance of the other wing K and thus cause the end of the blank bearing the outturned hook or edge fold x^1 to lap under the end of the blank having the inturned hook or edge fold x^2 . A turn-buckle K^6 is interposed between the connecting rod K^3 and strap K^2 for purposes of adjustment, and the rod K^4 has a threaded end and adjusting nuts K^7 for a similar purpose.

30 The bumper or seam squeezer L is preferably adjustably secured to a reciprocating cross head, preferably the same cross head H^2 which operates the lower or movable hook forming or edge folding dies H^1 .

35 The soldering horn M over and around which the can bodies pass after leaving the body former horn I is attached at its inner end to the body former horn I by a connecting bracket or angle plate m . It preferably consists of a plurality of rails or bars m^1 m^2 m^3 m^4 secured to a plurality of cross shaped spiders m^5 , the spiders being preferably in separate pieces from the rails. The upper soldering horn rail m^1 has a channel m^6 in its upper face to accommodate the pusher arms or fingers r of the upper conveyer R which moves the can bodies along the soldering horn in conjunction with the two lower conveyers R^1 . The two side rails m^2 m^2 are 40 preferably plain narrow flat bars fitting inside the can bodies and engaging its two parallel upright sides and serving in connection with the other bars m^1 and m^3 or m^4 to maintain the narrow flimsy sardine can bodies in proper shape as they are conveyed along the soldering horn. The two lower rails or bars m^3 which engage the can bodies 45 over the molten soldering receptacle or pot O , one on each side of the side seam of the can body are preferably composed of angle bars secured to the spiders m^5 parallel to each other and a short distance apart so as not to come in contact with the seam or with the molten solder that may be sweated 50 through the seam. The soldering horn rail

or bar m^4 at the lower edge of the horn at the part thereof over the fluxing device and which bears directly against the seam to hold it properly in contact with the fluxing device preferably consists of a plain rectangular bar. At its outer end, the soldering horn M is supported upon a revolving roller M^1 .

The fluxing device N preferably consists of an absorbent pad of felt or other like material supported in a suitable receptacle N^1 secured to the frame of the machine in advance of the molten solder receptacle O and by which the soldering device is held in contact with the side seam of the can body, 75 both the lock and the lap seam portion thereof, as the can body is moved along the soldering horn over the fluxing or acidizing device. The yielding character of the absorbent pad N enables it to properly engage 80 both the thinner or lap seam portion of the seam and the thicker or lock seam portion thereof.

The acid or flux in liquid form is automatically fed to the fluxing device N or its receptacle N^1 from a flux receptacle N^2 on the frame of the machine through a connecting pipe N^3 having a valve N^4 for regulating the flow. The molten solder receptacle or pot O is furnished with a gas burner 90 or other heating device O^1 for melting and keeping molten the solder, and with a leg O^2 having a slotted or curved top plate O^3 through which a narrow film of solder may come in contact with the side seam of the can body as the can body moves over this slotted top plate of the molten solder receptacle. The molten solder in the solder receptacle O is maintained at a slightly higher level as indicated at O^4 than the orifice or slot of the top plate O^3 of the soldering pot leg O^2 so that the hydrostatic action of the liquid will tend to maintain a slight film of solder in the slit or slot of the top plate O^3 as the solder is licked up by the seams of the cans passing over this slotted top plate. To maintain the molten solder in the pot O accurately and constantly at the required level, the solder is automatically fed in the form of wire solder Y to the soldering pot 100 through suitable wire solder feed rolls O^5 , the shaft O^6 of one of which is furnished with a ratchet O^7 engaged by a pawl O^8 on the lever O^9 which is actuated by a cam S^4 on the cam shaft S through a suitable connecting link O^{10} and lever O^{11} having a roller O^{12} at its end to engage the cam.

The conveyers R R^1 R^1 for moving the can bodies x^5 along the soldering horn M are preferably three in number, and each 115 consists of an endless flexible chain furnished with fingers or arms adapted to engage and push the can bodies along, one of these conveyer chains being arranged directly above the body former horn and the 120

other two below it, and to one side of its longitudinal center so that each can body will be simultaneously engaged by the pusher fingers or arms of all three chains, 5 the pusher fingers or arms of the two lower chains engaging the two lowermost corners of the can body and the pusher finger of the upper chain engaging the upper edge of the can body at its middle part. By this 10 means the short or narrow and flimsy sardine can bodies are uniformly and properly moved along the soldering horn without any tendency to tilt or bind or get askew and be crushed or injured and the machine clogged, 15 or to produce imperfectly soldered seams by reason of improper or inaccurate engagement of the side seam with the soldering and fluxing devices. Each of the conveyer chains R R¹ are furnished with pusher arms or 20 fingers r, those of the upper chain R riding in the channel m⁶ of the upper soldering horn rail or bar m¹, said rail thus serving also as a guide for the lower or operating member or loop of the upper conveyer chain, 25 R. The upper conveyer chain R is mounted upon and actuated by pulleys or sprocket wheels R² R³, one of which is furnished with a sprocket gear r¹¹ for engagement with the upright driving chain r² which travels on 30 sprocket wheels r³ r⁴, the latter being on the shaft r⁵. The shaft R⁴ of the sprocket wheel R³ is journaled in a movable bearing R⁵ which is furnished with a spring R⁶ to keep the conveyer R under proper tension, 35 The two lower conveyer chains R¹ are each mounted on pulleys or sprocket wheels R⁷ R⁸, the latter being on shaft r⁵ which is furnished with a beveled gear r⁶ that meshes with a beveled gear r⁷ on the shaft r⁸ which 40 carries a sprocket wheel r⁹ and is driven by a sprocket chain r¹⁰ from the sprocket gear S⁵ on the main driving shaft S; so that all three of the endless flexible conveyer chains R R¹ R¹ are simultaneously operated and in 45 unison, thus causing the can body pusher arms or fingers r on all three of the chains to simultaneously engage each of the can bodies. The shaft R⁹ of the sprocket wheels R⁷ is journaled in a movable bearing R¹⁰ 50 provided with springs R¹¹ for keeping the conveyers R¹ under proper tension.

S⁵ is the driving pulley and T the clutch for connecting and disconnecting the driving pulley with the driving shaft, the clutch 55 being operated by a clutch lever or treadle T through the intermediate lever T².

I claim:

1. In a can body machine, the combination with a magazine for body blanks, of a body 60 blank separator having an upper inclined face and a narrow ledge, a reciprocating body blank feeder for pushing the lowermost blank off said ledge, a reciprocating carrier for the body blanks furnished with a plurality of pusher fingers, tension shoes for

holding the blanks straight upon the carrier, notching dies, hook forming devices, a body former horn, wings for forming the blank around said horn, a bumper for squeezing the hooks into a lock seam at the middle portion of the can body, a soldering horn, a fluxing device, a molten solder receptacle having a leg with a slotted top plate below the level of the molten solder in said receptacle, a solder feed device and a plurality of conveyers furnished with pusher-arms, the pusher arms of all the conveyers simultaneously engaging each can body at its middle portion above the horn and at the corners below the horn, substantially as specified. 70 80

2. In a can body machine, the combination with a holder for the body blanks, of a separator having an upper inclined face and a narrow ledge, a feeder for pushing the lowermost blank off said ledge, and a carrier for the body blanks to which they are delivered one by one by said feeder, substantially as specified. 85

3. In a can body machine, the combination with a holder for the body blanks, of a separator having an upper inclined face and a narrow ledge, a feeder for pushing the lowermost blank off said ledge, and a carrier for the body blanks to which they are delivered one by one by said feeder, said feeder comprising a plurality of fingers each having a tapering front end to adapt it to pass under the pile of blanks in the holder, substantially as specified. 95

4. In a can body machine, the combination with a holder for the body blanks, of a separator having an upper inclined face and a narrow ledge, a feeder for pushing the lowermost blank off said ledge, and a carrier for the body blanks to which they are delivered one by one by said feeder, said feeder comprising a plurality of fingers each having a tapering front end to adapt it to pass under the pile of blanks in the holder, with a blank engaging device adapted to engage the lowermost blank only of the pile of blanks in the holder, substantially as specified. 100 105 110

5. In a can body machine, the combination with a holder for the body blanks, of a separator having an upper inclined face and a narrow ledge, a feeder for pushing the lowermost blank off said ledge, and a carrier for the body blanks to which they are delivered one by one by said feeder, said feeder comprising a plurality of fingers each furnished with a blank engaging device or shoulder adapted to engage the lowermost blank only of the pile of blanks in the holder, substantially as specified. 115 120

6. In a can body machine, the combination with a holder for the body blanks, of a separator having an upper inclined face and a narrow ledge, a feeder for pushing the lowermost blank off said ledge, and a carrier for the body blanks to which they are delivered 125 130

one by one by said feeder, said separator having an upper portion provided with a passage between its lower edge and said inclined face for the lowermost blank of the pile of blanks in the holder to pass through, substantially as specified.

7. In a can body machine, the combination with a holder for the body blanks, of a separator having an upper inclined face and a narrow ledge, a feeder for pushing the lowermost blank off said ledge, and a carrier for the body blanks to which they are delivered one by one by said feeder, said separator having an upper portion provided with a passage between its lower edge and said inclined face for the lowermost blank of the pile of blanks in the holder to pass through, and said separator being also provided with a tension device under which the lowermost blank passes as it is moved forward by the feeder and carrier, substantially as specified.

8. The combination with a blank holder, of a separator having an upper inclined face, a narrow shoulder upon which the pile of blanks rest, and a reciprocating feeder for pushing the lowermost blank of the pile off said shoulder onto said inclined face, substantially as specified.

30 9. The combination with a blank holder, of a separator having an upper inclined face and a narrow shoulder upon which the pile of blanks rest, a reciprocating feeder for pushing the lowermost blank of the pile off said shoulder onto said inclined face and a carrier having fingers adapted to engage the lowermost blank when resting in an inclined position on said inclined face, substantially as specified.

40 10. The combination with a blank holder, of a separator having an upper inclined face and a narrow shoulder upon which the pile of blanks rest, a reciprocating feeder for pushing the lowermost blank of the pile off said shoulder onto said inclined face, a carrier having fingers adapted to engage the lowermost blank when resting in an inclined position on said inclined face, edge folders, a body former horn, wings for forming the blank around the horn and a bumper, substantially as specified.

50 11. The combination with a blank holder, of a separator having an upper inclined face and a narrow shoulder upon which the pile of blanks rest, a reciprocating feeder for pushing the lowermost blank of the pile off said shoulder onto said inclined face, a carrier having fingers adapted to engage the lowermost blank when resting in an inclined position on said inclined face, edge folders, a body former horn, wings for forming the blank around the horn and a bumper, a soldering horn attached to said body former horn at its inner end, a fluxing device, a soldering device, and means for

moving the can bodies along the soldering horn, substantially as specified.

12. In a can body machine, the combination with body forming mechanism, of a body blank holder, a separator having an inclined face below said holder, and provided with shoulders for supporting the rear edge of the pile of blanks in the holder, and a reciprocating feeder adapted to engage the lowermost blank of the pile and push it off said shoulders so that it will rest in an inclined position on said inclined face of the separator, substantially as specified.

13. In a can body machine, the combination with a body former horn and means for forming the can body around the horn, of a soldering horn connected to said body former horn at its inner end having a channeled upper rail, side rails and lower rails spaced apart, a fluxing device and a soldering device and a plurality of endless flexible conveyors, each furnished with pusher fingers for moving the can bodies along said soldering horn, the fingers of one of said conveyors traveling in the channel of said upper rail of the soldering horn, and the fingers of the other two conveyors engaging the lowermost corners of the can bodies, substantially as specified.

14. In a can body machine, the combination with a body former horn and means for forming the can body around the horn, of a soldering horn connected to said body former horn at its inner end having a channeled upper rail, side rails and lower rails spaced apart, a fluxing device and a soldering device and a plurality of endless flexible conveyors, each furnished with pusher fingers for moving the can bodies along said soldering horn, the fingers of one of said conveyors traveling in the channel of said upper rail of the soldering horn, and the fingers of the other two conveyors engaging the lowermost corners of the can bodies, said soldering horn having a single lower rail ^{m⁴} at the portion thereof above which co-operates with said fluxing device, substantially as specified.

15. In a can body machine, the combination with a body former horn, of a soldering horn having an upper channeled rail and a pair of lower rails spaced apart, an endless flexible conveyor having pusher arms traveling in said channeled upper rail, and a pair of endless flexible conveyors having pusher arms adjacent the lower rails of the horn, substantially as specified.

16. In a can body machine, the combination with a body former horn, of a soldering horn having an upper channeled rail and a pair of lower rails spaced apart, an endless flexible conveyor having pusher arms traveling in said channeled upper rail, and a pair of endless flexible conveyors having pusher arms adjacent the lower rails of the

horn, and guides for the upper members of said lower conveyers to travel in, substantially as specified.

17. In a can body machine, the combination with a body former horn, of a soldering horn connected to said body former horn and around which the can bodies pass therefrom, a molten solder receptacle having a leg furnished with a slotted top plate to receive a narrow film of solder for application to the seam of the can body as it is moved over the same, said soldering horn bearing against the inner surface of the can bodies on each side of the seams thereof to hold and maintain the seam in coöperative relation with said narrow film of solder substantially as specified.

18. In a can body machine, the combination with a body former horn, of a soldering horn connected to said body former horn and around which the can bodies pass therefrom, a molten solder receptacle having a leg furnished with a slotted top plate to receive a narrow film of solder for application to the seam of the can body as it is moved over the same, and means for maintaining the molten solder in said receptacle at a level slightly above said slotted top plate to maintain a film of solder in the slot thereof, said soldering horn bearing against the inner surface of the can bodies on each side of the seams thereof to hold and maintain the seam in coöperative relation with said narrow film of solder substantially as specified.

19. In a can body machine, the combination with a body former horn, of a soldering horn connected to said body former horn and around which the can bodies pass therefrom, a molten solder receptacle having a leg furnished with a slotted top plate to receive a narrow film of solder for application to the seam of the can body as it is moved over the same, and a wire solder feed device for automatically maintaining the molten solder at the operating level in said solder receptacle, said soldering horn bearing against the inner surface of the can bodies on each side of the seams thereof to hold and maintain the seam in coöperative relation with said narrow film of solder substantially as specified.

20. In a can body machine, the combination with a body former horn, of a soldering horn connected to said body former horn and around which the can bodies pass therefrom, a molten solder receptacle having a leg furnished with a slotted top plate to receive a narrow film of solder for application to the seam of the can body as it is moved over the same, and means for moving the can bodies along said horn, said soldering horn bearing against the inner surface of the can bodies on each side of the seams thereof to hold and maintain the seam in coöperative

relation with said narrow film of solder substantially as specified.

21. In a can body machine, the combination with a body former horn, of a soldering horn connected to said body former horn and around which the can bodies pass therefrom, a molten solder receptacle having a leg furnished with a slotted top plate to receive a narrow film of solder for application to the seam of the can body as it is moved over the same, means for maintaining the molten solder in said receptacle at a level slightly above said slotted top plate to maintain the film of solder in the slot thereof, and means for moving the can bodies along said horn, said soldering horn bearing against the inner surface of the can bodies on each side of the seams thereof to hold and maintain the seam in coöperative relation with said narrow film of solder, substantially as specified.

22. In a can body machine, the combination with a body former horn, of a soldering horn connected to said body former horn and around which the can bodies pass therefrom, a molten solder receptacle having a leg furnished with a slotted top plate to receive a narrow film of solder for application to the seam of the can body as it is moved over the same, a wire solder feed device for automatically maintaining the molten solder at the operating level in said solder receptacle, and means for moving the can bodies along said horn, said soldering horn bearing against the inner surface of the can bodies on each side of the seams thereof to hold and maintain the seam in coöperative relation with said narrow film of solder, substantially as specified.

23. The combination with a soldering horn around which the can bodies pass, and means for moving the can bodies along the same, of a molten solder receptacle provided with a slotted top plate extending parallel to and below said horn, and means for forcing the molten solder through the slot of the top plate in a narrow film for engagement with the seams of the can bodies as they are moved along the horn in contact with said slotted top plate, said soldering horn bearing against the inner surface of the can bodies on each side of the seams thereof to hold and maintain the seam in coöperative relation with said narrow film of solder, substantially as specified.

24. In a can body machine, the combination with a body former horn, of a soldering horn connected at one end to the body former horn, a rotating roller supporting the outer end of said soldering horn, means for moving the can bodies along the soldering horn, a solder receptacle having a top plate furnished with a narrow slot parallel to and below said horn to receive a film of solder, said top plate engaging the side seam of the can

bodies as they are moved along the horn, substantially as specified.

25. In a can body machine, the combination with a body former horn, of a soldering horn connected at one end to the body former horn, a rotating roller supporting the outer end of said soldering horn, means for moving the can bodies along the soldering horn, a solder receptacle having a top plate furnished with a narrow slot parallel to and below said horn to receive a film of solder, said top plate engaging the side seam of the can bodies as they are moved along the horn, wire solder feed rolls and means for automatically operating said feed rolls to maintain the molten solder at a fixed level in said solder receptacle, substantially as specified.

26. The combination with a soldering horn having rails spaced apart for engagement with the can bodies, of a plurality of endless flexible conveyers having pusher arms simultaneously engaging each can body at three or more points on different sides of the horn, substantially as specified.

27. The combination with a soldering horn having rails spaced apart for engagement with the can bodies, of a plurality of endless flexible conveyers having pusher arms simultaneously engaging each can body at two or more points on different sides of the horn, substantially as specified.

28. In a can body machine, the combination with a soldering horn having a plurality of rails spaced apart, the upper rail having a channel, an upper conveyor having pusher arms traveling in said channel of said upper rail, and a pair of lower conveyers having pusher arms engaging the can bodies below and at each side of the horn, substantially as specified.

29. In a can body machine, the combination with a carrier for the can body blanks, consisting of a plurality of parallel bars furnished with a plurality of fingers, a magazine for the blanks, a blank separator having an inclined upper face against which the front corner of the pile of blanks in the magazine rests, and a narrow shoulder against which the rear edge of the pile of blanks rests, and a plurality of reciprocating feeder bars furnished with shoulders for engaging the lowermost blank of the pile and pushing it off said shoulder of the separator into position to be engaged by the fingers of the carrier, substantially as specified.

30. In a can body machine, the combination with a carrier for the can body blanks, consisting of a plurality of parallel bars furnished with a plurality of fingers, a magazine for the blanks, a blank separator having an inclined upper face against which the front corner of the pile of blanks in the magazine rests, and a narrow shoulder against which the rear edge of the pile of

blanks rests, and a plurality of reciprocating feeder bars furnished with shoulders for engaging the lowermost blank of the pile and pushing it off said shoulder of the separator into position to be engaged by the fingers of the carrier, said separator having an upper portion provided with a narrow space or opening between its lower edge and the upper inclined face of said separator, substantially as specified.

31. In a can body machine, the combination with a carrier for the can body blanks, consisting of a plurality of parallel bars furnished with a plurality of fingers, a magazine for the blanks, a blank separator, having an inclined upper face against which the front corner of the pile of blanks in the magazine rests, and a narrow shoulder against which the rear edge of the pile of blanks rests, and a plurality of reciprocating feeder bars furnished with shoulders for engaging the lowermost blank of the pile and pushing it off said shoulder of the separator into position to be engaged by the fingers of the carrier, said separator having an upper portion provided with a narrow space or opening between its lower edge and the upper inclined face of said separator, substantially as specified.

32. In a can body machine, the combination with a carrier for the can body blanks, consisting of a plurality of parallel bars furnished with a plurality of fingers, a magazine for the blanks, a blank separator having an inclined upper face against which the front corner of the pile of blanks in the magazine rests, and a narrow shoulder against which the rear edge of the pile of blanks rests, and a plurality of reciprocating feeder bars furnished with shoulders for engaging the lowermost blank of the pile and pushing it off said shoulder of the separator into position to be engaged by the fingers of the carrier, said separator having an upper portion provided with a narrow space or opening between its lower edge and the upper inclined face of said separator, the upper portion of said separator having a tension device under which the blank passes as it is moved forward by said carrier, substantially as specified.

33. In a can body machine, the combination with a carrier for the can body blanks, consisting of a plurality of parallel bars furnished with a plurality of fingers, a magazine for the blanks, a blank separator having an inclined upper face against which the front corner of the pile of blanks in the magazine rests, and a narrow shoulder against which the rear edge of the pile of blanks rests, and a plurality of reciprocating feeder bars furnished with shoulders for en-

gaging the lowermost blank of the pile and pushing it off said shoulder of the separator into position to be engaged by the fingers of the carrier, said separator having an upper portion provided with a narrow space or opening between its lower edge and the upper inclined face of said separator, and tension bars above said carrier bars under which the blanks pass as they are moved forward by the carrier bars, said tension bars having inclined ends to facilitate the entrance of the blanks beneath the same, substantially as specified.

34. In a can body machine, the combination with a holder for body blanks, of a body blank feeder, a carrier for the body blanks to which they are delivered one by one by said feeder, notching dies, hook forming devices, a body former horn, wings for wrapping the blank around said horn and a bumper for squeezing the hooks into a lock seam at the middle portion of the can body, substantially as specified.

35. In a can body machine, the combination with a holder for body blanks, of a body blank feeder, a carrier for the body blanks to which they are delivered one by one by said feeder, notching dies, hook forming devices, a body former horn, wings for wrapping the blank around said horn, a bumper for squeezing the hooks into a lock seam at the middle portion of the can body, a soldering horn, a fluxing device, a soldering device and means for moving the can bodies 35 along the soldering horn, substantially as specified.

36. In a can body machine, the combination with a carrier for the body blanks, of notching dies, hook forming devices, a body former horn, wings for wrapping the blank

around said horn, a bumper for squeezing the hooks into a lock seam at the middle portion of the can body, substantially as specified.

37. In a can body machine, the combination with a carrier for the body blanks, of notching dies, hook forming devices, a body former horn, wings for wrapping the blank around said horn, a bumper for squeezing the hooks into a lock seam at the middle portion of the can body, a soldering horn, a fluxing device, a soldering device and means for moving the can bodies along the soldering horn, substantially as specified. 45

38. In a can body machine, the combination with a carrier for the body blanks, of notching dies, hook forming devices, a body former horn, wings for wrapping the blank around said horn, a bumper for squeezing the hooks into a lock seam at the middle portion of the can body, a soldering horn, a fluxing device, a soldering device and a plurality of conveyers having fingers engaging each can body at a plurality of different points on different sides of the soldering 60 horn for moving the can bodies along the soldering horn, substantially as specified.

39. The combination with a soldering horn, of a solder applying device, an upper endless flexible conveyor having fingers engaging the can bodies at the upper portions thereof, and two lower endless flexible conveyors having fingers simultaneously engaging each can body at the lower portions thereof, substantially as specified. 70
